DESIGN FOR AN EASEL FOR DISPLAYING PLACARDS OR THE LIKE

Robert M. Allen, New York, N. Y.

Application August 1, 1933. Serial No. 48,905

Term of patent 14 years

To all whom it may concern:

Be it known that I, ROBERT M. ALLEN, residing at New York city, county and State of New York, a citizen of the United States, have invented a new, original, and ornamental Design for an Easel for Displaying Placards or the like, of which the following is a specification, reference being had to the accompanying drawing, forming part thereof.

In the drawing:

Fig. 1 is a front elevation of an easel for displaying placards or the like, showing my new design; and

Fig. 2 is a side elevation thereof.

I claim:

The ornamental design for an easel for displaying placards or the like as shown.

ROBT. M. ALLEN.
